CLAIM

The ornamental design for a chromatograph, as shown and described.

DESCRIPTION

FIG. 1 is a front perspective view of a chromatograph; FIG. 2 is a rear perspective view of the chromatograph illustrated in FIG. 1;

FIG. 3 is a front elevation view of the chromatograph illustrated in FIG. 1;

FIG. 4 is a right side elevation view of the chromatograph illustrated in FIG. 1;

FIG. 5 is a rear elevation view of the chromatograph illustrated in FIG. 1;

FIG. 6 is a left side elevation view of the chromatograph illustrated in FIG. 1;

FIG. 7 is a top plan view of the chromatograph illustrated in FIG. 1; and,

FIG. 8 is a bottom plan view of the chromatograph illustrated in FIG. 1.

In the drawings, the consistent length broken lines show portions of the chromatograph that form no part of the claimed design. Further, the dash-dot broken lines boundary and area within form no part of the claimed design.

1 Claim, 8 Drawing Sheets
